UNITED STATES PATENT OFFICE.

JOHN D. RIPSON, OF ROCHESTER, NEW YORK, ASSIGNOR TO THE FLOWER CITY CASKET COMPANY, OF SAME PLACE.

DESIGN FOR A CASKET.

SPECIFICATION forming part of Design No. 25,498, dated May 12, 1896.

Application filed March 6, 1894. Serial No. 502,590. Term of patent 7 years.

To all whom it may concern:

Be it known that I, JOHN D. RIPSON, of Rochester, Monroe county, State of New York, have invented or produced a new and original Design for Burial-Caskets, of which the following is a specification.

In the drawings, Figure 1 is a plan view of a casket, showing my new design. Fig. 2 is a side elevation of the same, and Fig. 3 is an enlarged side elevation of one end of the casket.

A indicates the casket, and B the lid. The new feature in my design consists of an ornamental cap at each corner composed of two parts *c d*. The lower part *c* is of double ogee form and is enlarged, as shown, forming a continuation of the top molding of the casket. The center portion of the same comes to a

thin edge. The upper part *d* is in the form of a half-globe, with a small nipple or projection at the top. This cap stands outward from the corners of the casket and presents an ornamental appearance, as it surmounts a column *b*, set in a recess of the casket.

Having described my invention, what I claim as new, and desire to secure by Letters Patent, is—

The design for a burial-casket herein shown and described.

In witness whereof I have hereunto signed my name in the presence of two subscribing witnesses.

JOHN D. RIPSON.
